Attorney

UNITED STATES PATENT OFFICE.

ADAM HOLEMAN, OF BRONSON, KANSAS.

GATE-LATCH.

SPECIFICATION forming part of Letters Patent No. 283,243, dated August 14, 1883.

Application filed January 19, 1883. (No model.)

To all whom it may concern:

Be it known that I, ADAM HOLEMAN, a citizen of the United States, residing at Bronson, in the county of Bourbon and State of Kansas, 5 have invented certain new and useful Improvements in Gate-Latches, of which the following is a specification, reference being had therein to the accompanying drawings.

My invention relates to improvements in wire 10 gates or the latches therefor; and it consists in the construction, combination, and arrangement of the several parts, as will be hereinafter fully described, and specifically pointed out in the claim.

15 In the drawings, Figure 1 is a side view of my gate. Fig. 2 is a plan view of the gate latched, with dotted lines showing the same unlatched, and Fig. 3 is a plan view of the gate when being fastened or unfastened, as will 20 be described.

The gate is composed of the wires *a* and the bar *a'*.

b is the post. The wires *a* are secured at one end in any suitable manner to the said post, as shown, and their opposite ends are 25 made fast to the bar *a'*.

a' is an eye or staple, secured to the bar *a'* in position to be entered by the lever-latch, hereinafter described.

30 *c* is the butt-post, to and away from which the bar *a'* swings in the operation of the device. *c'* is a lug extended from the butt-post.

d is the lever-latch, having its inner end pivoted on the lug *c'*, and swinging laterally, 35 as will be described. This lever is constructed so that its outer end may be passed through the staple *a'*, and is provided on what (for convenience of reference) I call its "outer left side," with a slot, *d'*, arranged close to its piv-

40 otal point, as shown. In the inner end of this slot I cut the notch *d''*, while its outer end is beveled slightly, so that the staple will slide off easily when the lever-latch is turned to the right to release the same.

In the operation of my invention, when it 45 is desired to latch the gate, the bar *a'* is swung in close to the butt-post, and the outer end of the lever-latch is passed through the staple *a'*, and the lever is then swung to the position shown in Fig. 2, the staple falling into the slot 50 *d'* and notch *d''* therein, in which position it will be seen that all force or strain on the gate will draw the fastening together, rather than otherwise, the strain of the gate being exerted on the latch in rear of the pivotal point of the 55 same.

It will be understood that instead of cutting the slot in the outer side of the lever a small projection could be formed thereon near the pivoted end and adapted to hold the staple. 60 I prefer, however, the construction shown, inasmuch as it is easier made, stronger, and more efficient. In either case, it will be seen that the object is to provide a shoulder on the outer side of the lever arranged in proper position 65 to secure the staple when the lever is turned, as shown.

My invention is particularly useful in making gates in wire fences, it being only necessary to cut the wires at a post and secure the 70 ends to the gate-bar, having the staple secured thereto, and then fix the lever-latch on the post from which the wire has been cut, and the gate is complete.

What I claim is—
75 In combination with a gate for wire fences, constructed as described, the latch consisting of the lever *d*, pivoted to the lug *c'* of the post *C*, said lever being formed with a slot, *d'*, and notch *d''*, adapted to receive the staple *a'* of the 80 gate, substantially as set forth.

In testimony whereof I affix my signature in presence of two witnesses.

ADAM HOLEMAN.

Witnesses:

J. W. HOLEMAN,
S. F. POWERS.
